LAY MOTION FOR LOOMS

William W. Robertson, Northboro, Mass., assignor
to Crompton & Knowles Loom Works, Worcester, Mass., a corporation of Massachusetts

Application April 11, 1936, Serial No. 73,863

9 Claims. (Cl. 139—190)

This invention relates to improvements in mechanism for operating lays of relatively wide and heavy looms and it is the general object of the invention to provide an auxiliary brace to exert a force at a point intermediate the length of the lay to prevent backward bending thereof at the time of beat-up.

In relatively heavy carpet looms the reed is subjected to considerable backward force by the fabric at the time of beat-up. When the loom is relatively wide this bending leaves a noticeable curve in the pattern of the fabric being woven. Ordinarily the lay is driven by two connectors from a driving shaft, the connectors being located near the ends of the loom outside the space reserved for the harness frames. The latter are in such a position as to interfere with an intermediate connector, and it is an important object of my present invention to provide a toggle joint located in front of the harness frames and having two links one of which is operatively connected to the lay and the other of which operates from a fixed point on the loom frame, the toggle being operated by a cam set and designed to give the intermediate part of the lay a forward motion the same as that derived from the crank connectors at the ends of the lay. When the loom is running idle without warp the toggle joint will close without effort, but when the loom is weaving any tendency on the part of the intermediate portions of the lay to bend backwardly will be resisted by straightening of the toggle. By the use of my invention the dents of the reed are maintained in alignment and the successive rows of tuft yarns lie in a straight line transverse of the fabric.

It is a further object of my present invention to arrange the toggle and actuator therefor so that the toggle links do not become completely aligned, thereby permitting the toggle to bend without locking the lay as the latter recedes from forward position. This is particularly desirable when the operating force is derived from a face cam.

It is a further object of my invention to provide means to assist the lay in moving the toggle links during its forward motion. As the toggle links approach a straight or aligned relation the effort to lift them increases and this effort I somewhat relieve by a spring interposed between one of the toggle links and preferably a part moving with the lay rocker shaft. It is desirable that the spring be free from tension when the lay is forward so that as the lay starts backwardly the links will be free to drop by gravity without being resisted by the spring. During forward motion of

the lay from its rear position, however, the spring will be under maximum tension to furnish part of the force required to lift the links toward their aligned position.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a vertical transverse section through a portion of a loom having my invention applied thereto,

Fig. 2 is a diagrammatic plan view of a portion of the loom having the crank connectors for the end of the lay and the toggle joint to brace the center thereof,

Fig. 3 is a view similar to a portion of Fig. 1 with the lay in rear position and the toggle broken, and

Fig. 4 is a vertical section on line 4—4 of Fig. 3.

Referring particularly to Fig. 1, the loom frame 16 supports crank and bottom shafts 11 and 12, respectively, which are geared together by a 2 to 1 ratio indicated at 13 in Fig. 3. The top shaft 11 makes one complete revolution for each forward beat of the lay L, while the bottom shaft requires two beats of the loom for a complete revolution. The loom has a breast beam 14 with a cloth board 15 and a take-up roll 16 for the woven fabric. There are two lay swords 17 and 18, one adjacent each end of the lay, and each sword is mounted on a rocker shaft 19 journaled in the bottom of the loom frame.

Connectors 20 are interposed between the cranks 21 of the shaft 11 and the lay swords, and as the crank shaft 11 makes one complete revolution the lay moves from the forward position shown in Fig. 1 to the rear position shown in Fig. 3 and back again to the forward position of Fig. 1. The matter thus far described is of common construction and operates in the usual manner.

In carrying my present invention into effect I provide an intermediate stand 30 which is rigid with the loom frame and provided with a pivot pin 31 in the upper rear portion thereof located in front of the crank shaft 11. Pivot on this pin is a rear toggle link 32 the forward end of which is pivoted as at 33 to a second or forward toggle link 34. The latter extends into the forked end 35 of the rear link 32.

A bracket 36 is secured to the under side of the lay beam 37 and has a pin 38 in the forward end

thereof to which link 34 is pivoted. A stop screw 39 on the rear link 32 is adjusted to engage block 40 formed as part of the bracket 36, and the purpose of this stop screw is to prevent the centers 5 31, 33 and 38 from becoming aligned. The center 33 is always below a line joining the pivots 31 and 38.

The bottom shaft 12 has secured thereto a cam 50 having two lobes 51 and 52, respectively, which 10 alternately engage a roll 53 on a lever 54 pivoted as at 55 to the intermediate frame 30. The forward arm 56 of lever 54 is pivoted as at 57 to an upwardly extending rod 58 pivoted as at 59 to the forked end 35 of the rear link 32. The two 15 lobes 51 and 52 are 180° apart so that as the two-pick shaft 12 rotates, lever 54 will be given a complete oscillation for each beat of the loom.

The rear link 32 has a depending arm 65 connected as at 66 to the rear end of a tension spring 20 67 the forward end of which is connected as at 68 to an arm 69 adjustably clamped or otherwise secured to the oscillating rocker shaft 19. By this latter construction the angular relation between the arm 69 and the lay swords, and therefore the lay beam, is maintained fixed. The relation between the arms 65 and 69 is such, however, that when the parts are positioned as set forth in Fig. 3 the rear end of the spring has moved rearwardly a greater distance than the forward end thereof, hence the spring is under maximum tension when the lay is in the rear position set forth in Fig. 3. When the lay is forward the effect of the differential motions of the arms 65 and 69 renders the spring slack.

35 The lobes 51 and 52 are so designed that they preferably have driving relation with respect to the rolls 53 and therefore the lever 54 at such times only as the lay is near its front center position, shown in Fig. 1. Furthermore, the outer 40 or pointed ends of these cams are so constructed as to give the toggles such a character of motion as will move the central part of the lay beam forwardly at a rate substantially the same as that derived from the connectors of the crank shaft.

45 In operation, the top and bottom shafts turn in the usual manner, the top shaft effecting a movement of the lay from the rear position in Fig. 3 to the forward position of Fig. 1 during substantially a half revolution of the crank shaft. 50 During the greater part of this motion the cam 50 is out of driving relation with respect to the roll 53 and the toggle links will assume the kind of relation shown in Fig. 3. As the lay approaches forward position, however, one or another of the 55 lobes of the cam will rock lever 54 in a left hand direction as viewed in Figs. 1 and 3 to elevate the rod 58, thereby causing the toggle links to approach an aligned position.

By the construction of the cam lobes already 60 described the center portion of the lay is moved forwardly by the toggle at a rate substantially the same as that of the lay ends which derive their motions from the crank shaft, hence the lay beam will assume the full line position shown in Fig. 3 65 and be prevented from bowing backwardly to the dotted line position of that figure. As soon as the crank shaft starts to move the lay rearwardly the toggle links 32 and 34 together with the rod 58, by reason of their weight, will tend to break the 70 toggle so that said links fall in time to avoid interference with rearward lay motion derived from the crank shaft. The cam lobes 51 and 52 are designed to permit this character of motion without interference on the part of lever 54.

75 When the parts are in the position shown in

Fig. 3 the spring 67 is under greatest tension and as the lay starts to move forwardly the arm 69 will advance to the right as viewed in Fig. 3 thereby exerting a pull on said spring the effect of which is to rock the link 32 in a left hand direction as viewed in Fig. 3 about the axis of 31. This has the effect of assisting the lay in straightening the toggle links, but as the lay approaches its forward position the connection 66 moves forwardly faster than the connection 68 10 and just at the extreme front center position of the lay the spring 67 is slackened so that it will not interfere in any way with the breaking of the toggle under the action of gravity when the lay starts rearwardly. The arm 69 can be 15 clamped in adjusted angular position with respect to the rocker shaft 19 by means of the clamp screws 80 so as to vary the action of spring 67.

From the foregoing it will be seen that I have 20 provided a simple means for bracing the intermediate part of the lay beam to maintain the latter straight across the loom at the time of beat-up, thereby insuring the weaving of fabrics the patterns of which are in correct alignment. It will 25 further be seen that the cam which drives the toggle joints effects a motion on the part of the center of the lay substantially the same as that of the lay ends derived from the crank shaft. Furthermore, it will be seen that the spring 30 assists the lay in lifting the toggle joint toward the straightened position shown in Fig. 3, the spring however becoming slack just before the lay reaches extreme forward position so that the links 32 and 34 will be free to drop with the action 35 of gravity when the lay starts backwardly. It will also be seen that screw 39 prevents the toggle links from becoming completely aligned, thereby 40 insuring easy dropping of the toggle links by gravity.

Having thus described my invention it will be seen that changes and modifications may be made therein by those skilled in the art without departing from the spirit and scope of the invention and I do not wish to be limited to the details 45 herein disclosed, but what I claim is:

1. In a lay motion for a loom having a frame, a lay, a crank shaft, connectors between the shaft and lay adjacent the ends of the latter, means defining a toggle between the lay and loom frame 50 at a point between the connectors, means to prevent complete straightening of the toggle, a spring tending to straighten the toggle when the lay is in rear position, and means operative as the lay approaches forward position to exert 55 a positive force on the toggle to move the latter toward straightened position and thereby prevent rearward bending of the lay.

2. In a lay motion for a loom having a frame, a lay, a crank shaft, connectors between the shaft 60 and lay adjacent the ends of the latter, means defining a toggle between the lay and loom frame at a point between the connectors, means to prevent complete straightening of the toggle, a spring 65 interposed between the lay and toggle tending to straighten the toggle when the lay is in rear position, and means operative as the lay approaches forward position to exert a positive force on the toggle to move the latter toward straightened position and thereby prevent rearward bending of the lay.

3. In a lay motion for a loom having a frame, a lay, a crank shaft, connectors between the shaft and lay adjacent the ends of the latter, a toggle 70 link connected to the lay at a point between the 75

- connectors, a second toggle link pivoted to the loom frame and pivoted to the first link, yielding means between the lay and one of the links tending to move said links into alignment, stop means 5 to prevent alignment of the links, and means operative as the lay approaches forward position to exert a positive force on the links tending to align the links to brace the intermediate part of the lay against rearward bending during the forward motion thereof.
4. In a lay motion for a loom having a frame, a lay, a crank shaft, connectors between the shaft and lay adjacent the ends of the latter, means defining a toggle between the lay and loom frame at 15 a point between the connectors, means to prevent complete straightening of the toggle, yielding means tending to straighten the toggle, a regularly moving cam, a cam lever moved positively in one direction by the cam, and connections between the lever and toggle to exert a force on 20 the toggle derived from the cam when the latter moves in said one direction and the lay approaches forward position to move the toggle toward straight position and thereby prevent rearward bending of the lay.
5. In a lay motion for a loom having a frame, a lay, a crank shaft, connectors between the shaft and lay adjacent the ends of the latter, a toggle link connected to the lay at a point between the 25 connectors, a second toggle link pivoted to the loom frame and the first link, yielding means between the lay and one of the links tending to align the links, means to prevent alignment of the links, and positively acting means to move the links toward alignment as the lay approaches forward position, the lay and link connected to the yielding means operative during backward motion of the lay to increase the tendency of the yielding means to move the links toward alignment.
- 40 6. In a lay motion for a loom having a frame, a crank shaft, connectors between the crank shaft and the ends of the lay, a rocker shaft for the lay, a toggle link pivoted to the lay between the connectors, a second toggle link pivoted to the loom frame and to the first link, an arm depending from one of the links, a second arm secured to and moving with the rocker shaft, a spring connected to the arms, means to prevent alignment of the links, a cam, and means operated by the 45 cam and operatively connected to one of the links as the lay moves forwardly to move the

links toward alignment, the arms being disposed to decrease the force exerted by the spring during the forward movement of the lay and increase said force during backward movement of the lay.

7. In a lay motion for a loom having a frame, a crank shaft, connectors between the shaft and the ends of the lay, a toggle link pivotally connected to the lay intermediate the connectors, a second toggle link pivoted to the frame and pivotally connected to the link, an arm depending from said second link, a rocker shaft for the lay, an arm extending upwardly from the rocker shaft in front of the first named arm, a spring connected to the arms, the arms proportioned and moving at such rates that as the lay approaches forward position the arm on the rocker shaft moves forwardly at a rate slower than that at which the said arm on the second link moves forwardly, and means to prevent alignment of the links, the force exerted by the spring decreasing as the lay approaches front center and increasing as the lay recedes from front center.

8. In a lay motion for a loom having an intermediate frame between the ends of the loom, a crank shaft, connectors between the shaft and the ends of the lay, a toggle link pivotally connected to the intermediate frame at a point in front of the crank shaft, a second toggle link pivotally connected to the lay at a point intermediate the ends thereof and to the first link, means to prevent alignment of the links, and means to exert a momentary force on the links tending to move them toward alignment and cause them to move the lay at a rate substantially the same as that caused by the connectors as the lay approaches forward position.

9. In a lay motion for a loom, a frame with an intermediate portion between the ends of the loom, a crank shaft, connectors between the crank shaft and the ends of the lay, means located entirely in front of the crank shaft constituting a toggle between the intermediate portion of the frame and the lay at a point intermediate the connectors, and means operative as the lay approaches forward position to move the toggle toward straight position at a rate to cause the intermediate part of the lay connected to the toggle to move forwardly at substantially the same rate as the rate at which the ends of the lay are moved by the connectors.

WILLIAM W. ROBERTSON.
